UNITED STATES PATENT OFFICE.

ADOLPH GERSON, OF NEW YORK, N. Y.

WATCH.

No. 866,198.

Specification of Letters Patent.

Patented Sept. 17, 1907.

Application filed June 1, 1907. Serial No. 376,796.

To all whom it may concern:

Be it known that I, ADOLPH GERSON, a subject of the Emperor of Germany, residing at New York city, Manhattan borough, county and State of New York, 5 have invented certain new and useful Improvements in Watches, of which the following is a clear, full, and exact description.

This invention relates to watches, the object being to produce a watch case that can be cheaply manufactured, special means being provided for removably holding the watch mechanism within the outer casing by means of the stem. My improved watch case is particularly adapted for cheap grades of watches, being so constructed and assembled as to provide a dust- 15 proof covering for the mechanism, without the necessity of any exact fittings.

My invention comprises the novel features of improvement and combination and arrangement of parts, which I will now proceed to describe and finally claim, 20 reference being had to the accompanying drawing, which forms part of this specification, wherein—

Figure 1 illustrates a sectional view of the outer member of my improved watch case, the inner container or holder being in elevation and partly in section; Fig. 25 2 is a detail top plan view, partly in section, of the outer member of my improved watch-case; Fig. 3 is a detail view in elevation, of the inner container or holder of my improved watch-case, partly in section, showing a portion of the watch mechanism therein 30 contained; Fig. 4 is an enlarged fragmentary detail view, showing the winding stem which forms the reusable locking device for the inner container or holder of the case; and Fig. 5 is a diagrammatic view of the mechanism with which the stem co-acts.

Like numerals of reference indicate similar parts in the several views.

Referring to the drawing, 1 indicates the outer member, or shell, of my improved watch case, while 2 indicates the inner container or holder for the watch mechanism, which is diagrammatically indicated by the numeral 3 (Fig. 3). For the sake of clearness, the winding stem side of the shell will be hereinafter termed the front, and the opposite side the back. At the back of the shell 1, I place a nib 4 (Figs. 1 and 2) 45 which extends sufficiently from the shell 1 to enter an opening 5 in the container 2 when the said holder or container is in position in the shell 1, as shown in Fig. 1. The nib 4 can be soldered or otherwise secured to the shell 1. The front of the shell 1 is provided with 50 the usual neck 6 which contains the pendant 7 of the variety used in most stem-winding and stem-setting watches. The pendant 7 carries the usual winding and setting stem 8 which, at its inner end, is squared and adapted to enter the rotatable square bored bush- 55 ing 9 which forms part of the watch mechanism and is not in itself a part of my invention.

To fulfil the object of my invention I have modified the stem 8 to the extent of adding a stop 10, the object of which will hereinafter appear. The operation of the stem for winding the main spring and setting the 60 hands of a watch is well known, but a brief description thereof will now be given in order to bring out one of the features of my improvement.

The stem 8 is longitudinally movable in the pendant 7 and when pushed to its innermost position the 65 squared end 11 thereof will be contained within the square bore 12 of the bushing 9 to an extent sufficient to cause the clutch 13 to remain disengaged from the jaws 14 and engage with the jaws 15 (Fig. 5) whereby the gear 16, which is attached to the jaws 15, is free 70 to revolve with the bushing 9 owing to the square end cylindrical spindle 17, the gear 16 being loose on the spindle 17, and the square end 18 of spindle 17 being slidably fitted to the bore 12 of the bushing 9. When the stem 8 is in their innermost position, and revolved, 75 the gear 16, which meshes with the gear 19, which in turn is geared to the main spring of the mechanism, is caused to wind up the said main spring. Fig. 1 illustrates the stem in the winding position. In order to set the hands of the watch, the stem 8 is pulled outwardly until the 80 stop 20 contacts the pendant 7. When in the latter position the spring 21 will have pushed the spindle 17 and clutch 13 thereon away from the gear 16 and into mesh with the jaws 21 of the gear 22, which by means of the gear 23 operates the hand-setting mechanism. The 85 hands of the watch can now be set by rotating the stem 8, the spring winding mechanism remaining idle (see dotted lines 24, Fig. 5). The winding and setting mechanism *per se* forms no part of my invention and is referred to simply to set forth an operative mechanism. 90 As can be seen in Figs. 1 and 4 the holder or container 2 is provided with an opening 25 large enough to allow the square end 11 of the stem 8 to pass therethrough and into the bore 12 of the bushing 9. When the stem 8 is in either the setting or winding position, the said 95 square end 11 of the stem 8 will still be within the opening 25; therefore the holder or container 2 cannot be removed, as it will be held down by the said squared end 11 and the nib 4. To prevent the holder or container 2 from rattling, or from being prematurely displaced, I have provided a spring 26 adjacent to the nib 4 (see Fig. 2), retaining brackets 27 being provided to keep the spring from getting out of register with the said nib 4. The spring 26 acts to force the holder or container 2, when in position, forwardly toward the stem, 105 whereby sufficient friction, between the case 1 and the holder or container 2, is caused to prevent the member 2 from being easily displaced. The full lines in Fig 2 indicate the position of the spring 26 when the holder or container is removed, and the dotted lines indicate 110 the position of the spring when the container is in position.

As can be seen by Fig. 4, the outer shell 1 is provided at the top thereof with a rounded upwardly extending annular flange 28 which is adapted to snugly fit an annular recess 29 in the container or holder 2, the said 5 recess being formed between the wall 30 of the said holder or container 2 and a downwardly extending annular flange 31 carried thereby. The said holder or container 2 is also provided with a bezel 32 which receives the crystal 33.

10 It is obvious from the foregoing description that the holder or container 2 and shell 1 are held together by means of the winding stem 8, nib 4 and spring 26 together with the opening 5 in the holder or retainer 2 and the bushing 9 of the watch mechanism, while the 15 joint made by the flange 28 and recess 29 renders the case dust-proof. To remove the holder or container 2, it is but necessary to pull out the stem 8 to its full extent whereby the squared end 11 thereof will be freed from the bushing 9 and opening 25 in the wall 30 of the 20 holder or container (see Fig. 4). The holder or container 2 can then be lifted at a slight angle until the nib 4 is free from the opening 5, and the holder or container can then be removed for the purpose of cleaning or fixing the mechanism. The function of the extra stop, 25 10 is for the purpose of causing the stem 8 to perform a triple function. Ordinarily there is one stop 20 and a collar or final stop 34, the stop 20 usually being normally against the end of the pendant 7, for the winding position, and the final stop 34 for the setting position, 30 the stop 20 being in this latter instance pulled into the pendant 7. In my arrangement the final stop 34 does not come in contact with the pendant 7, until it is desired to take the holder or container 2 out. The stem 8

therefore is adapted for a triple purpose, viz: for winding the main spring, for setting the hands when pulled 35 out to the extent of one stop on the stem, and for releasing the holder or container when pulled out the full extent.

Having now described my invention, what I claim and desire to secure by Letters Patent is:

1. A watch comprising an outer shell, an upwardly extending annular flange carried by said shell, a removable holder for the watch movement within said shell, said holder being provided with an annular grooved portion adapted to fit the annular flange on said outer shell, said 45 annular grooved portion being provided with a bezel for the crystal.

2. A watch comprising an outer shell, an upwardly extending annular flange carried by said shell, a removable holder for the watch movement within said shell, said holder being provided with an annular grooved portion adapted to fit the annular flange on said outer shell, said 50 annular grooved portion being provided with a bezel for the crystal, and means, controlled by the winding stem for said movement, adapted to releasably hold said holder 55 in position.

3. A watch comprising an outer shell, an upwardly extending annular flange carried by said shell, a removable holder for the watch movement within said shell, said holder being provided with an annular grooved portion adapted to fit the annular flange on said outer shell, said 60 annular grooved portion being provided with a bezel for the crystal, a removable container within said shell adapted to hold the movement, and means, controlled by the winding stem for said movement, adapted to releasably 65 hold said container in position.

Signed at New York, N. Y., this 29 day of May, 1907.

ADOLPH GERSON.
